COMBUSTION CHAMBER WITH CROSSOVER
TUBES

Arthur W. Gaubatz, Indianapolis, Ind., assignor
to General Motors Corporation, Detroit, Mich.,
a corporation of Delaware

Application October 21, 1950, Serial No. 191,417

6 Claims. (Cl. 60—39.32)

1

My invention relates to combustion apparatus such as are commonly used in gas turbine engines. Such combustion apparatus commonly comprises a number of generally cylindrical and approximately parallel combustion chambers fed by a common compressor and discharging combustion products into a common turbine. The combustion chambers are disposed in an annular arrangement with each chamber supplying an arcuate portion of the annular nozzle of the turbine.

Since such engines and combustion chamber arrangements are well known, I deem it unnecessary to describe them further. The general arrangement of a particular engine to which my invention may be applied is described in an article by Robert Hotz in Aviation Week, volume 51, number 23; pages 11 to 13 (December 5, 1949).

Combustion apparatus of the type referred to above commonly comprises perforated flame tubes within and generally concentric with the combustion chambers, within which the actual combustion takes place. It is common practice to interconnect the combustion chambers and flame tubes by concentric tubular arrangements commonly referred to as crossover tubes. Such crossover tubes comprise in effect an inner tube joining each adjacent pair of flame tubes and an outer tube or shell interconnecting the casings of adjacent chambers. The purpose of the flame tubes is to provide for ignition of the fuel in one chamber from that adjacent to it, so that a spark plug or the like need not be installed in each combustion chamber. The crossover tubes also serve to some extent to equalize the pressures between the combustion chambers.

My invention is directed to an improved crossover tube of the type referred to. The principal advantages of the invention are simplicity, airtightness, adequate provision for thermal expansion, and ease of assembly and disassembly. This last advantage is more important than it might appear to be because of the close quarters in which gas turbine engines are frequently installed in aircraft and the need for rather frequent inspection and servicing of the combustion apparatus. In the event of failure of a combustion chamber, or parts thereof, it should be possible to replace the defective parts with a minimum of disassembly of the engine and a minimum expenditure of time. The problem of easy assembly and disassembly of the combustion apparatus is particularly severe in installations such as are described in the above-noted article, in which two gas turbine power units are

2

located side by side with small clearance between the units.

The principal objects of the invention are to improve combustion apparatus for gas turbines and the like, to facilitate the servicing of such engines, and to provide an improved crossover tube structure for multiple chamber combustion apparatus.

The manner in which the objects and advantages of the invention are realized will be apparent to those skilled in the art from the appended description of the preferred embodiment of the invention.

Referring to the drawing, Figure 1 is a partial cross-sectional view of a gas turbine engine illustrating the relative arrangement of a number of combustion chambers; Figure 2 is an enlarged longitudinal section of the crossover tube arrangement of the invention, taken on the plane indicated in Figure 3; and Figure 3 is a sectional view, taken on the plane indicated in Figure 2, to a somewhat smaller scale than Figure 2.

The combustion chambers A, B, C, and D (Fig. 1) form as illustrated a part of a group of eight 25 combustion chambers arranged symmetrically about an axis in close side by side relation. Each combustion chamber comprises an outer shell 11 of sheet metal. A flame tube 12 is installed in each combustion chamber, being mounted in any 30 suitable manner. Each shell 11 is formed with two openings 13 (Fig. 2) over each of which is secured a collar 14, as by a weld 16 at the outer edge of a flange 17 at the base of the collar 14 abutting the casing 11. Preferably, the casing is 35 flat at the area of engagement with the flange 17. For an arrangement of eight combustion chambers, the collars 14 are preferably fixed to the combustion chamber at a spacing of 135 degrees with respect to the axis of the casing 11 so that the collars 14 of adjacent casings are in alignment when the combustion chambers are installed in the engine, the collars extending radially from the casings.

The flame tubes 12 are formed with flanged 45 circular ports 18 aligned with the axis of the collars 14. The adjacent flame tubes 12 are in communication through inner crossover tubes, each comprising two sections 19 of thin-walled heat resisting tubing formed with flanges 20 at their adjacent or outer ends. The unflanged or inner ends of the tube sections 19 are inserted in the flanged ports 18 of the flame tubes with the flanged adjacent ends 20 of the tubes 19 abutting as shown in Figure 2. The flanges 20 50 of the tube sections 19 lie between inwardly di-

rected flanges 21 of the collars 14, the spacing between the flanges 21 being slightly greater than the total thickness of the two flanges 20. The flanges 21 are cut out or scalloped as indicated at 22, leaving projecting portions 23 (Fig. 3) between the scallops which engage the outer surface of the inner tubes 19 to locate and center these tubes. The scallops 22 extend to the base of the flange 21 and beyond the outer diameter of the flanges 20, so that air may flow through the collars 14 between the combustion chambers 11.

A considerable space is left between the ends of the collars 14. Escape of air through this gap is prevented by a split sleeve 24 comprising two semi-cylindrical sections 26 and 27 and expanding piston ring seals 28 engaged in grooves in the outer surface of the collars 14 and bearing against the cylindrical inner surface of the sleeve 24. Preferably, there are two seals 28 mounted in each collar 14 near the outer end thereof. The axial length of the sleeve 24 is considerably greater than the extreme distance between seals 28 but somewhat less than the distance between the faces of the flanges 17, so that relative expansion of the combustion chambers may take place freely and the sleeve may slide back and forth or rotate on the seals.

The two halves 26 and 27 of the sleeve are formed with outwardly-extending lugs which are bored for studs 31 (Fig. 3), the member 27 being tapped to receive the studs and the sleeve being held assembled by nuts 32 on the studs.

The two collars 14, the sleeve 24, and the seals 28 constitute a substantially airtight outer crossover tube between adjacent combustion shells 11, and the tubes 19 constitute a crossover between adjacent flame tubes 12 providing for flame propagation between the flame tubes. Air flow longitudinally of the chambers 11 and between the chambers through the outer tube cools the crossover tubes 19, which are heated to a considerable extent by heat radiated from the flames in the flame tubes 12.

The invention greatly facilitates installation and removal of the combustion chambers. For normal installation, the flame tube 12 is installed in the casing 11 in whatever manner is appropriate to the structure of these elements, with the ports 18 of the flame tubes aligned with the openings 13 of the casings. The inner crossover tube sections 19 are slipped into the ports of the flame tubes until they bear against the flanges 21 of the collars 14. The combustion chambers are then installed between the compressor and turbine of the engine. It is then necessary only to fit the two halves of the sleeve 24 over the rings 28 and tighten the nuts 32 to complete the assembly. The nuts 32 are easily accessible.

For disassembly, to remove a combustion chamber, all that is normally necessary, so far as the crossover tube structure is concerned, is to remove the nuts 32 and the sleeves 24 between the combustion chamber to be removed and the two adjoining combustion chambers.

It will be noted, moreover, that where engines are in close side by side relation, a combustion chamber may be installed or removed without the necessity of applying or removing the nuts 32 of a relatively inaccessible sleeve with the combustion chambers in place. For example, if it is desired to install the combustion chamber indicated as B in Figure 1 with the combustion chamber identified as A in place, the sleeve 24 may

be assembled over the collar 14 of combustion chamber A and then, by compressing the ring seals 28 of the collar 14 of combustion chamber B, these rings may be slipped into the sleeve 24. It will be noted that the ends of the sleeve are slightly chamfered, as indicated at 33 in Figure 2, to facilitate this operation. Ordinarily, in a side by side power unit mounting, only one crossover tube of each power unit is inaccessible with the combustion chambers in place. Thus, assuming that the crossover tube between chambers A and B is installed with the sleeve already assembled as just described, the remaining crossover tubes such as those between chambers B and C and between C and D may be installed with the sleeves removed and the sleeves then assembled. For removal of a casing 11, the collar 14 slips readily out of the sleeve 24.

Thus, the combustion chambers may be put in place or removed without any difficult problems of assembling or disassembling the crossover tubes. Where the proximity of another power unit makes it inconvenient to separate the halves of the sleeve 24, the sleeve may be left in place and the combustion chamber moved slightly to one side to remove or insert the collar 14 in the sleeve 24.

The advantages of the invention in simplicity, reliability, provision for free expansion of the elements, and ease of assembly and disassembly will be apparent to those skilled in the art from the foregoing description of the preferred embodiment of the invention. It will also be apparent to those skilled in the art that many modifications of structure may be made within the principles and scope of the invention, which are not to be regarded as limited by the detailed description of the preferred embodiment thereof.

I claim:

1. A combustion apparatus comprising a plurality of combustion chambers, flame tubes therein, the chambers and tubes being formed with aligned lateral openings facing similar openings in the adjacent chambers and tubes; collars fixed to the chambers in alignment with the said openings; a sleeve extending over the collars, the sleeve being slidable with respect to the collars; sealing means between each collar and the sleeve; tube sections coupled to the flame tubes extending through the collars to provide crossover tubes between the flame tubes, the ends of the tube sections of each crossover tube remote from the flame tubes being adjacent to each other; and means for directly supporting and locating the adjacent ends of the tube sections from the collars for limited freedom of movement axially of the collars.

2. A combustion apparatus comprising a plurality of combustion chambers, flame tubes therein, the chambers and tubes being formed with aligned lateral openings facing similar openings in the adjacent chambers and tubes; collars fixed to the chambers in alignment with the said openings; a sleeve, comprising two semi-cylindrical parts and means for securing the parts together, extending over the collars, the sleeve being slidable with respect to the collars; sealing means between each collar and the sleeve; tube sections coupled to the flame tubes and extending through the collars to provide crossover tubes between the flame tubes, the ends of the tube sections of each crossover tube remote from the flame tubes being adjacent to each other; and means for locating the adjacent ends of the tube sections in the collars.

3. A combustion apparatus comprising a plurality of combustion chambers, flame tubes therein, the chambers and tubes being formed with aligned lateral openings facing similar openings in the adjacent chambers and tubes; collars fixed to the chambers in alignment with the said openings; a sleeve extending over the collars, the sleeve being slideable with respect to the collars; sealing means between each collar and the sleeve; tube sections coupled to the flame tubes and extending through the collars to provide crossover tubes between the flame tubes, the ends of the tube sections of each crossover tube remote from the flame tubes being adjacent to each other and the said ends being flanged outwardly; and means for locating the adjacent ends of the tube sections in the collars with limited freedom of movement axially of the collars comprising flanges extending radially inwardly from the collars adjacent the ends of the collars remote from the combustion chambers and engaging the tube sections between the flanges on the tube sections and the combustion chamber into which the respective tube sections extend.

4. A combustion apparatus comprising a plurality of combustion chambers, flame tubes therein, the chambers and tubes being formed with aligned lateral openings facing similar openings in the adjacent chambers and tubes; collars fixed to the chambers in alignment with the said openings; a sleeve extending over the collars, the sleeve being slideable with respect to the collars; sealing means between each collar and the sleeve; tube sections coupled to the flame tubes and extending through the collars to provide crossover tubes between the flame tubes, the ends of the tube sections of each crossover tube remote from the flame tubes being adjacent to each other and the said ends being flanged outwardly; and means for locating the adjacent ends of the tube sections in the collars with limited freedom of movement axially of the collars comprising spaced projections extending radially inwardly from the collars adjacent the ends of the collars remote from the combustion chambers and engaging the tube sections between the flanges on the tube sections and the combustion chamber into which the respective tube sections extend.

5. A combustion apparatus comprising a plurality of combustion chambers, flame tubes therein, the chambers and tubes being formed with aligned lateral openings facing similar openings in the adjacent chambers and tubes; collars fixed to the chambers in alignment with the said openings; a sleeve extending over the collars, the

sleeve being slideable with respect to the collars; sealing means between each collar and the sleeve; tube sections coupled to the flame tubes and extending through the collars to provide crossover tubes between the flame tubes, the ends of the tube sections of each crossover tube remote from the flame tubes being adjacent to each other and the said ends being flanged outwardly; and means for locating the adjacent ends of the tube sections in the collars with limited freedom of movement axially of the collars comprising spaced projections extending radially inwardly from the collars adjacent the ends of the collars remote from the combustion chambers and engaging the tube sections between the flanges on the tube sections and the combustion chamber into which the respective tube sections extend; the distance between opposed projections on opposed collars being greater than the combined thickness of the two tube section flanges between the projections.

6. A combustion apparatus comprising a plurality of combustion chambers, flame tubes therein, the chambers and tubes being formed with aligned lateral openings facing similar openings in the adjacent chambers and tubes; collars fixed to the chambers in alignment with the said openings; a sleeve extending over the collars, the sleeve being slideable with respect to the collars; sealing means between each collar and the sleeve; tube sections slidably coupled to the flame tubes extending through and slidably supported by the collars to provide removable crossover tubes between the flame tubes, the ends of the tube sections of each crossover tube remote from the flame tubes being adjacent to each other; the tube sections being mounted in the collars free from the sleeve so that adjacent combustion chambers may be coupled or uncoupled by sliding a collar and the tube section therein into or out of the sleeve.
